UNITED STATES PATENT OFFICE.

MONTAGUE H. ROBERTS, OF PROVIDENCE, RHODE ISLAND.

FLUID-PRESSURE MOTOR.

1,118,053.

Specification of Letters Patent. Patented Nov. 24, 1914.

Application filed May 3, 1912. Serial No. 694,840.

To all whom it may concern:

Be it known that I, MONTAGUE H. ROBERTS, of Providence, in the county of Providence and State of Rhode Island, have invented a certain new and useful Improvement 5 in Fluid-Pressure Motors, of which improvement the following is a specification.

My invention more particularly relates to fluid pressure motors of the internal combustion type, although not specifically limited to such type, and its object is to provide a valve mechanism therefor, which shall be of simple and inexpensive construction, and which, in operation, shall be exempt 10 from unbalanced pressure and thrust, and be capable of either manual or automatic control for the functions of varying the point of cut-off or reversal of direction of rotation of the motor, or of acting as a 15 brake.

The improvement claimed is hereinafter fully set forth.

In the accompanying drawings: Figure 1 is a vertical transverse central section 25 through a fluid pressure motor, illustrating an embodiment of my invention; Figs. 2 and 3, horizontal sections through the same, on the lines *a a* and *b b*, respectively of Fig. 1; Fig. 4, a view, in perspective, of the 30 throttle sleeve; and Fig. 5, a similar view of the inlet valve.

My invention is herein exemplified in an internal-combustion engine, which except as to the features of my invention as hereinabove described, is of the ordinary construction, comprising a cylinder, 1, located above and secured to a closed crank case, 2, in which is journaled a crank shaft, 3, carrying a crank, 3^a, the crank pin, 3^b, of which 35 is coupled, by a connecting rod, 4, to a piston, 5, reciprocating in the cylinder, 1. The cylinder is closed at top by a head, 6, having a water jacket, 6^a, to which, and 40 to a water jacket, 1^a, surrounding the cylinder, water is supplied through a pipe, 6^b. The engine is fitted with other accessories 45 which are common to motors of this type, and which, as they do not relate to my present invention, will not be herein described.

50 In the practice of my invention, the cylinder, 1, is reduced in diameter at and adjacent to its lower end, and a cut off valve, 7, which I herein designate as a throttle sleeve, and which is in the form of an open 55 ended tubular member, finished truly on its outer and inner surfaces, is fitted to recipro-

cate within the cylinder, on the reduced diameter portion of which it has its lower and outer bearing, and, at and adjacent to its upper end, it has its upper and inner bearing on the periphery of the inwardly projecting portion of the cylinder head, 6. An inlet port, 7^a, and an opposite exhaust port, 7^b, are formed in the throttle sleeve, said ports being located in position to be brought into register, respectively, with an inlet port, 8, and an exhaust port, 9, on opposite sides of the cylinder. A lug, 7^c, is formed on or fixed to the lower end of the throttle sleeve, for the connection of operating mechanism hereinafter described.

The admission and exhaust of motive fluid to and from the cylinder, 1, above the piston, 5, are effected by an inlet valve, 10, and an exhaust valve, 11, each of which is in the form of a segmental plate, finished truly on its inner and outer surfaces, said valves being interposed, and fitted to reciprocate, between the bore of the cylinder, 1, and the periphery of the throttle sleeve, 7. The inlet valve, 10, is provided with a port, 10^a, near its upper end, in position to be brought into register with the inlet port, 8, of the cylinder, and a lug or pair of jaws, 10^b, is formed or fixed on its lower end, for connection with an operating shaft. The exhaust valve, 11, is similarly provided with a port, 11^a, near its upper end, in position to be brought into register with the exhaust port, 9, of the cylinder, and a lug or pair of jaws, 11^b, is formed or fixed on its lower end, for connection with an operating shaft.

An inlet valve operating shaft, 12, is journaled parallel with the crank shaft, 3, on one side thereof, and an exhaust valve operating shaft, 13, is similarly journaled on the opposite side of the crank shaft. A timing gear, 14, fixed on the crank shaft, engages a gear, 15, of larger diameter on the inlet valve operating shaft, and a similar gear, 16, on the exhaust valve operating shaft, rotation being thereby imparted to the valve operating shafts, in the usual manner. The gears, 14, 15, and 16, are indicated by dotted circles in Fig. 1.

The inlet valve, 10, is reciprocated by the shaft, 12, through a rod, 17, connected to the jaws, 10^b, at the lower end of the valve, and passing through a guide bushing, 17^a, fixed in the lower end of the cylinder, 1, the lower end of the rod, 17, being coupled, by a connecting rod, 18, to a crank or eccentric on

the shaft, 12. The exhaust valve, 11, is similarly reciprocated by the shaft, 13, through a rod, 19, connected to the jaws, 11^a, at the lower end of the valve, and passing through 5 a guide bushing, 19, fixed in the lower end of the cylinder, 1, the lower end of the rod, 19, being coupled, by a connecting rod, 20, to a crank or eccentric on the shaft, 13.

The throttle sleeve, 7, being, as before explained, guided at top by its internal bearing on the cylinder head, 6, and at bottom by its external bearing on the bore of the cylinder, it will be seen that the inlet and outlet valves, which fit against its periphery, 10 are entirely relieved from thrust or pressure exerted by the piston. They are also free to expand and contract, both longitudinally and circumferentially; are not subject to any unbalanced pressure; and are removed 15 from contact with the explosive mixture which exerts operative pressure on the piston in the combustion chamber between the latter and the cylinder head.

The throttle sleeve, 7, is fitted to be reciprocated, with the capacity of variation of the degree and direction of its movement, and the cessation thereof, as from time to time it is desired to vary the point of cut off, to reverse the direction of rotation of the 20 crank shaft, or to entirely close communication between the combustion chamber above the piston and the cylinder inlet and exhaust ports. To this end, the lower end lug, 7^a, of the throttle sleeve is coupled by means of a 25 depending lug and by a pin, 7^b, see Fig. 1, to a link motion valve operating gear, comprising a block 21^a, fitting a longitudinal slot in a segmental valve link, 21, and eccentric rods, 22, 23, by which the link, 21, is coupled, adjacent to its ends, to cranks or eccentrics on one of the valve operating shafts, in this instance the inlet valve operating shaft, 12. The link, 21, is coupled, by a rod, 24, to an arm, 25, fixed on a control or regulating shaft, 26, which may be swung in its bearings, by a manually operated lever, or by a connection to an automatic governor, to vary the position of the link longitudinally 40 relatively to the block, and thereby to vary 45 the point of cut off or to reverse the direction 50 of cut off.

tion of rotation of the engine, in the well known manner of valve gears of this type.

By moving the link to its central or mid position, the reciprocating movement of the throttle sleeve will be substantially stopped, 55 and communication closed between the combustion chamber above the piston and the cylinder inlet and exhaust ports, the movements of the piston then causing it to act as a vacuum brake. It will also be seen that 60 by proper adjustments of the link, the degree of compression in the combustion chamber may be varied as desired.

I claim as my invention and desire to secure by Letters Patent:

65

1. In a fluid pressure motor, the combination of a fixed cylinder having inlet and exhaust ports, a piston reciprocating therein, a sleeve or tubular cut off valve fitted to reciprocate between the cylinder and the piston, 70 said valve having ports registerable with the inlet and exhaust ports and bearing on fixed cylindrical surfaces of said cylinder at its opposite ends, segmental inlet and exhaust valves, each having a port registerable with 75 one of the ports of the cut off valve and fitted to reciprocate between said valve and the cylinder, means for reciprocating the cut off valve, and means for independently reciprocating the inlet and outlet valves. 80

2. In a fluid pressure motor, the combination of a fixed cylinder having inlet and exhaust ports, a piston reciprocating therein, a sleeve or tubular cut off valve fitted to reciprocate between the cylinder and the piston, 85 said valve having ports registerable with the inlet and exhaust ports and bearing on fixed cylindrical surfaces of said cylinder at its opposite ends, a segmental valve having a port registerable with a port of the cut off 90 valve and fitted to reciprocate between said valve and the cylinder, a guide, fixed to the cylinder, for said segmental valve, means for reciprocating the cut off valve, and means for independently reciprocating the segmental valve. 95
